UNITED STATES PATENT OFFICE.

JOHN M. LESSELLS, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSFORMER RADIATOR.

Application filed December 21, 1920. Serial No. 432,355.

My invention relates to radiators, and it has particular relation to radiators adapted for utilization with transformer cooling systems.

One of the objects of my invention is to provide a radiator of the character described having a relatively large radiating surface, as compared with the space occupied thereby.

Another object is to provide a transformer radiator having a compact arrangement of the various elements and one that may readily be assembled and disassembled with a minimum of time and labor.

Heretofore, certain types of transformer radiators have been constructed of a plurality of separate and independent radiators arranged radially around the periphery of a transformer tank. These radiators generally comprise a plurality of vertically extending and communicating units arranged in spaced and parallel relation with each other. Each of the units have, heretofore, been constructed with substantially the same cross-sectional dimensions. When a plurality of complete radiators comprising units of such dimensions were arranged in position around the periphery of a transformer tank, the edges of the respective units of each adjacent radiator lay in diverging planes.

Such a construction was undesirable for the reason that considerable available space between the adjacent radiators was unoccupied. This unoccupied space increased outwardly as the space defined by the sides diverged, and was considerably greater than was necessary for an effective circulation of air.

According to my invention, I form the separate units of each radiator with the cross-sectional areas thereof having different transverse dimensions. When the units so formed are assembled with the size of the units progressively increasing outwardly from the tank to constitute a complete radiator, the vertical edges of the several units of adjacent radiators will lie in substantially parallel planes.

By means of this construction, the total radiating surface is greater than that heretofore obtained without necessarily increasing the overall diameter of a transformer tank and the radiators carried thereby.

In the accompanying drawings,

Figure 1 is a plan view of a transformer

having a plurality of radiators mounted 55 thereon constructed in accordance with my invention.

Fig. 2 is a fragmentary view, partly in elevation and partly in vertical section, of a 60 transformer tank and radiators.

Referring to the drawings, 1 indicates a transformer tank having a plurality of radially extending radiator elements 2, mounted around the periphery thereof by means of couplings 3. The radiators each comprise 65 a plurality of separately formed communicating units or cells 4 arranged in spaced and parallel relation.

The side walls 5 of each of the units are preferably formed of sheet metal blanks 70 pressed into the desired shape and welded or otherwise suitably secured together. Each of the side walls 5 may be provided with a plurality of vertically extending reinforcing indentations 6. The upper and 75 lower extremities of each of the side walls 5 are preferably formed with extensions 7 having extruded portions 8 and apertures 9 adapted to register with the corresponding 80 extrusions and apertures of an adjacent unit to effect communication therebetween.

For convenience in manufacture, the units 4 are preferably arranged in groups, the major dimensions of the cross-sectional areas of the units of each respective group 85 being substantially the same. The transverse dimensions of the cross-sectional areas of the units of each group are greater, however, than those of the adjacent group nearest the center. That is to say, the confronting edges 90 of each pair of units of the adjacent radiators lie substantially in parallel planes, the distance between the innermost unit determining the distance between the adjacent radiators. 95

The units may be formed with ever increasing major dimensions with respect to the cross-sectional areas thereof. Such construction, however, requires dies or other suitable forming tools of correspondingly 100 varying sizes. It is, therefore, preferred to construct a radiator of group units, the units of each group having the same size and with the edges of the respective groups arranged in spaced relation, as above set forth. 105

The construction of a radiator of grouped units of the same size, does not materially affect the distance between adjacent radia-

tors, as the difference in size of the units of the different groups is so slight as to make a relatively small step.

I claim as my invention:

- 5 1. A cooling system comprising a receptacle containing a medium to be cooled, a plurality of radiators arranged radially around the periphery of said receptacle and communicating therewith, said radiators comprising a plurality of communicating units, the cross-sectional areas of which have varying major dimensions.
- 10 2. A cooling system comprising a receptacle containing a medium to be cooled, a plurality of radiators arranged radially around the periphery of said receptacle and communicating therewith, said radiators comprising a plurality of communicating units arranged in spaced and parallel relation, the cross-sectional areas of which have varying major dimensions.
- 15 3. A cooling system comprising a receptacle containing a medium to be cooled, a plurality of radiators arranged radially around the periphery of said receptacle and communicating therewith, said radiators each comprising a plurality of communicating units, the units of one radiator being substantially the same distance from the
- 20 30 corresponding units of the adjacent radiator.

4. A cooling system comprising a receptacle containing a medium to be cooled, a plurality of radiators arranged radially around the periphery of said receptacle and communicating therewith, said radiators each comprising a plurality of communicating units, the cross-sectional areas of certain of said radiators having increasing transverse dimensions progressing outwardly from said receptacle.

5. A cooling system comprising a tank and a plurality of radiators each comprising a plurality of communicating units connected thereto, said radiators being so shaped and so arranged relatively to each other as to provide therebetween an unobstructed space for a column of circulating air substantially of rectangular cross-section.

6. A cooling system comprising a tank and a plurality of radiators each comprising a plurality of vertically extending units connected thereto, said radiators being so shaped and so arranged relatively to each other as to provide therebetween a space for a column of circulating air, the main portion of which is substantially of rectangular cross-section.

In testimony whereof, I have hereunto subscribed my name this 30th day of November, 1920.

JOHN M. LESSELLS.
